UNITED STATES PATENT OFFICE.

LUCIEN STEPHEN CRANDALL, OF BIRMINGHAM, ENGLAND.

DRIVING-GEAR.

SPECIFICATION forming part of Letters Patent No. 599,689, dated March 1, 1898.

Application filed May 24, 1897. Serial No. 637,942. (No model.)

To all whom it may concern:

Be it known that I, LUCIEN STEPHEN CRANDALL, a citizen of the United States of America, residing at 62 Moor street, in the city of 5 Birmingham, England, have invented certain new and useful Improvements in Driving-Gear, of which the following is a specification.

This invention consists of improvements in driving-gear for cycles and other machines, 10 my object being to provide simple and efficient means for the transmission of power and to so arrange the same that the ratio between the speeds of the driving and driven parts can be very readily and conveniently 15 varied.

In order that my invention may be the more readily understood, I append hereunto three sheets of explanatory drawings, to be 20 hereinafter referred to.

Figure 1 is a side elevation of a bicycle fitted with my improved driving-gear. Figs. 25 4 to 13, inclusive, are illustrations, to a larger scale, of the details of my improved driving-gear. Fig. 2 is a side elevation, and Fig. 3 an end elevation, representing my gear in one 30 combination. Figs. 4 and 4^A are sectional views illustrating the connection between the gear and the rear wheel of a cycle. Fig. 5 is a side elevation representing the gear adjusted 35 to such a position as to give the minimum ratio between the speeds of the driving and driven parts. Fig. 6 is a side elevation, and Fig. 7 a part sectional end elevation, representing a modified form of the connection between the gear and the rear wheel of a cycle. Fig. 8 is a side elevation, and Fig. 9 an end 40 elevation, representing my gear in another combination. Fig. 10 is a side elevation, and Fig. 11 an end elevation, representing my gear in a further combination and in position for maximum speed ratio; and Fig. 12 is an 45 end view showing the combination of anti-friction-balls with the eccentric. Fig. 13 illustrates the combination shown at Figs. 10 and 11 in position for minimum speed ratio.

The same reference-letters in the different views indicate the same parts.

In the application of my invention to a cycle such as illustrated at Fig. 1 I secure upon 50 the crank or driving shaft or spindle (indicated by the letter A in the detail views) in

place of the ordinary chain-wheel employed in chain driving-gear an eccentric sheave B, and on the end of the bracket or bearing adjacent thereto I mount an adjusting worm 55 wheel or block C. The worm D upon the spindle D' gears into the worm-block C, and adjustment can thus be effected by turning the hand-wheel D² on the upper end of the spindle D', such hand-wheel being arranged in 60 a convenient position for operation by the rider without dismounting and while the machine is in motion.

The eccentric sheave B imparts a reciprocating or oscillating motion to the lever E, pivoted 65 upon a link F, which is connected to the projecting arm C, such arm being integral with the worm-block C. One end of the lever E embraces the eccentric sheave B, while the opposite end is jointed to the pitman G. Thus 70 on the revolution of the crank-shaft a reciprocating motion is imparted to the pitman G.

A slotted or shackle-like end G' is provided at the rear part of the pitman G to receive the operating-clutches H H'. Each of the 75 clutches H H' is mounted loosely upon rollers carried on the projection J from the rear-wheel hub and is prevented from lateral displacement from the slotted or shackle-like end G' by the fixed flange J' on the one side 80 and the movable flange J² on the opposite side. The flange J² is removed from the views at Figs. 2 and 5. The clutches each consist of a ring having an external flange at each side and a plain internal surface which rides 85 upon the projecting boss J. Grooves or recesses, as J³, are formed in the boss J for the reception of the rollers, as illustrated at Figs. 2 and 5.

Within the slot or shackle end G' of the pitman G, I secure a pair of wire or other flexible cords, as K K', one at the upper and the other at the lower side. One end of the cord K', Figs. 2, 4, and 5, is secured in any convenient manner to the shackle at a, and the opposite end is then passed completely around the clutch-ring H', Figs. 4 and 4^A, and after the cord is pulled tight throughout its length such end is secured to the shackle at b. In the same manner the lower cord K is secured to 95 the shackle and passes around the clutch-ring H; but whereas the cord K' is led around the 100

clutch-ring H' from its upper side the cord K is led around the clutch-ring H from the under side, and thus as the pitman G is reciprocated the clutch-rings will be revolved in 5 opposite directions.

On the movement of the pitman G in the direction indicated by the arrow 1, Fig. 2, the clutch-ring H' will be revolved in the direction indicated by the arrow 2, causing its rollers 10 to be retained against the shouldered ends of the grooves or recesses J³, and thus no motion will be imparted to the rear wheel; but at the same time the clutch-ring H will be revolved in the direction indicated by the arrow 3 and its rollers will be moved away from the shouldered ends of the grooves or recesses and toward the narrow ends, and thus by becoming wedged between the clutch-ring and the projecting boss J will lock the two parts 15 and cause them to revolve together. On the reverse movement of the pitman G the clutch-ring H' and the rear wheel will be revolved together in the direction of the arrow 3, while the clutch-ring H will revolve idly in the opposite direction. Thus by the continuous reciprocation of the pitman the driving-wheel 20 will be constantly revolved in the required direction.

Each clutch-ring is provided with its own 25 set of rollers, the ring L being interposed between them. The eye of the ring L is formed to suit the section of the projecting boss J.

The illustrations Figs. 2 and 3 show the lever E set in the position to give the maximum ratio between the speeds of the crank-shaft and the rear or driving wheel of the bicycle for the particular pivot-eye which is mounted upon the pintle or pivot-pin of the link F. The position illustrated is suitable 35 for pedaling the machine over a flat road or when only a moderate tractive force is required and the rider wishes the distance travelled by the machine to be the maximum multiple of the movement of the pedals.

40 The illustration Fig. 5 shows the lever E set in the position to give the minimum ratio between the speeds of the crank-shaft and the rear or driving wheel, the length of the reciprocating movement of the pitman G being now limited to twice the throw of the eccentric B. Such position is suitable for hill-climbing or when a considerable tractive force 45 is required upon the driving-wheel.

The position of the lever E can be readily 55 adjusted to any point between the speed position shown at Fig. 2 and the hill-climbing position shown at Fig. 5 by the operation of the hand-wheel D², Fig. 1, and, as hereinbefore described, such operation can be effected by 60 the rider without dismounting and while the machine is in motion.

The lever E can be pivoted upon the link F at any of the pivot-eyes e to suit the rider. By pivoting at the eye nearest to the crank-shaft A the maximum possible ratio between 65

the speeds of the crank and the driving-wheel will be obtained.

In the combination illustrated at Figs. 6 and 7 I dispense with the cord connection between the pitman and the clutches, as hereinbefore described, and provide teeth upon the exterior surfaces of the clutch-rings to engage with rack-teeth formed in the shackle end of the pitman, the rack-teeth, which are equal in width to one of the clutch-rings or 70 one-half the width of the pitman, being arranged at the upper and lower sides, respectively, as illustrated at Figs. 6 and 7, in order to cause the clutch-rings to revolve in opposite directions. 80

In the combination shown at Figs. 8 and 9 the lever E' is pivoted at its lower extremity and has its connection with the eccentric B between its two ends or extremities. The lever in this case is therefore a lever of the 85 "third kind," having the power or operating force applied between the fulcrum and the load or resistance to be overcome, whereas the lever in Figs. 2 and 3 is of the "first kind," having the fulcrum between the operating force and the resistance. 90

In the combination illustrated by Figs. 10 to 13, inclusive, on Sheet 3, the lever E² is provided with a central aperture for the reception of the eccentric, which is made in two 95 parts and has antifriction-balls carried in a retaining-groove around its periphery, as illustrated in a large sectional view of a portion of the eccentric at Fig. 12. The lower end of the lever E² is pivoted directly upon 100 the projecting arm C' from the worm-block C. With such a combination the minimum horizontal or effective movement of the pitman G on the revolution of the eccentric is limited to the distance indicated at M, Fig. 13. 105

Having now described my invention, what I claim as new, and desire to secure by Letters Patent, is—

1. In a cycle driving-gear, the combination with the crank-shaft and driving-wheel, of 110 an oscillating lever pivotally connected to the cycle-frame, a cam carried by the crank or driving shaft and directly engaging one end of said lever for oscillating the same, and a pitman extending from the opposite end of 115 said oscillating lever to the hub of the driving-wheel and having a pawl-and-ratchet connection therewith, substantially as described.

2. In a cycle, the combination with the crank-shaft and driving-wheel, of the oscillating lever pivotally connected to the cycle-frame, a cam carried by the crank-shaft directly engaging one end of said lever for oscillating the same, independent clutch-rings carried by the driving-wheel, and a pitman 120 extending from the opposite end of the oscillating lever to said clutch-rings and having its upper side connected with one clutch-ring and its lower side connected with the other clutch-ring, substantially as described. 125 130

3. In a cycle, the combination with the crank-shaft and driving-wheel, of the oscillating lever, the adjustable block carried by the cycle-frame, the lever having its fulcrum connected with said adjustable block, the cam carried by the crank-shaft for oscillating said lever, and the pitman extending from the oscillating lever and having a pawl-and-

ratchet connection with the driving-wheel, substantially as described.

In witness whereof I have hereunto set my hand in presence of two witnesses.

LUCIEN STEPHEN CRANDALL.
